US0D1110432S

(12) **United States Design Patent** (10) **Patent No.:** **US D1,110,432 S**
(45) **Date of Patent:** **** Jan. 27, 2026**

(54) **MODEL VEHICLE SPOILER**

(71) Applicant: **TRAXXAS, L.P.**, McKinney, TX (US)

(72) Inventors: **Randy Perez**, McKinney, TX (US);
Kent Poteet, Lucas, TX (US); **Adam Cole Ewing**, McKinney, TX (US); **Otto Karl Allmendinger**, Rowlett, TX (US);
Terry Soward, Van Alstyne, TX (US);
Jory Sprowl, Howe, TX (US)

(73) Assignee: **TRAXXAS, L.P.**, McKinney, TX (US)

(**) Term: **15 Years**

(21) Appl. No.: **29/944,803**

(22) Filed: **May 30, 2024**

(51) LOC (15) Cl. **21-01**

(52) U.S. Cl.

USPC **D21/561**; D21/562; D21/533

(58) **Field of Classification Search**

USPC D21/561, 533, 562, 565, 424, 595, 495,
D21/489, 491; D12/159

CPC A63H 17/262; A63H 18/08
